FORM SEPARATOR

Carl Lather, Chicago, Ill., assignor to Redi-Rip Company, Milwaukee, Wis., a partnership

Application July 6, 1948, Serial No. 37,282

5 Claims. (Cl. 164—84.5)

1

This invention relates to a form separator and particularly has reference to a machine for separating form sheets from carbon sheets interposed between the form sheets to make a plurality of copies of the writing or typing on the uppermost or original sheet of the set.

Forms such as duplicate invoices and the like are made up in sets comprising the original and duplicate form sheets with carbon paper interposed between the respective sheets for purposes of reproduction. The form sheets are made with perforations near the top of each sheet to facilitate separating the sheets from the set. The carbon paper interposed between the form sheets is not perforated as are the form sheets and does not extend to the bottom edge of the form sheets. This construction of the pad or set permits the form sheets to be separated from the set by pulling them out together and without disturbing the carbons which are then discarded.

The principal object of the invention is to provide a simple, compact, portable machine for separating the completed forms from carbon paper interposed therebetween.

Another object is to provide a machine for separating completed forms from carbon paper interposed therebetween which tends to separate the forms from the set by tearing them from one end to the other.

Another object is to provide a form separator which is readily adjustable for handling forms of different size.

A further object of the invention is to provide a form separator which can be employed in separating only a few pages of forms from carbon paper interposed therebetween, or a substantial number.

These and other objects of the invention will appear hereinafter in connection with the following description of an embodiment of the invention illustrated in the accompanying drawing.

In the drawing:

Figure 1 is a side elevational view of a form separator constructed in accordance with the invention;

Fig. 2 is a top plan view of the form separator of Fig. 1;

Fig. 3 is a side elevational view of the form separator of Fig. 1 illustrating the position of the parts after form sheets have been separated from the carbon paper in the set;

Fig. 4 is a section taken on line 4—4 of Fig. 2;

Fig. 5 is a section taken on line 5—5 of Fig. 1;

Fig. 6 is a section taken on line 6—6 of Fig. 1;

2

Fig. 7 is an enlarged side elevational view illustrating a set or pad of forms to which the invention is applied; and

Fig. 8 is a top plan view of the set of forms of Fig. 7 with different sheets broken away to illustrate the construction of the pad.

Referring to the drawings the form separator there shown for purposes of illustration comprises in general the movable base member 1 and the stationary base member 2 for supporting the machine on a table or the like and which are joined by a pair of spaced horizontally extending rods 3. The rods 3 are secured to stationary base member 2 near the top and pass through the sockets 4 located adjacent the top of base member 1 and also the base member proper itself. Base member 1 may be moved longitudinally of rods 3 to regulate the spacing between member 1 and member 2 to accommodate sets of forms of different length. When located as desired the knurled set screws 5 in the side of base member 1 are tightened against the rods 3 to secure the base member 1 against movement relative to base member 2. If desired, any suitable means (not shown), such as a rack on each rod 3 and a cross-shaft in base 1 with pinions meshing with the corresponding racks, may be employed to move base member 1 along both rods 3 simultaneously.

Fig. 1 in elevation illustrates one position of base member 1 with respect to base member 2 and the dotted lines show base member 1 in its extended position to accommodate a pad of forms of considerable length. The machine is constructed of a width to handle standard size sets of forms over a considerable range of different widths.

The movable base 1 has a flat table-like top 6 which in fact serves as the lower jaw of the holding clamp to be described and upon which rests the head 7 of a set of forms such as those generally designated as 8 in Figs. 7 and 8. The holding clamp has the upper jaw member 9 with a transverse pivot shaft which is journaled in the bearing lugs 10 provided in transversely spaced relation on the rear portion of the base top or lower jaw 6.

The lever arm 11 extends outwardly from jaw 9 of the clamp to facilitate pivoting of the clamp by the operator to an open and closed position. The thin edge 12 which may be serrated, if desired, extends downwardly from the forward end of jaw 9 to engage head 7 of the set of forms 8 resting on base top 6 and clamp the same tightly against base top 6 under pressure from

the operator on lever arm 11 when the clamp is swung to closed position. When open an abutment on the rear of the jaw 9 engages an abutment 13 on base top 6 to limit the movement of the clamp.

The clamp for gripping and separating the form sheets 14 from the carbon sheets 15 of the set of forms 8, as illustrated in Figs. 7 and 8, is secured to the stationary base member 2. The separating clamp has a flat top lower jaw 16 which, when the clamp is open, lies on a plane slightly above that of the top of the forward upright 17 of base member 2. The upper jaw 18 cooperates with lower jaw 16 to complete the clamp.

The legs 19 extend downwardly from each side of lower jaw 16 and are pivoted to base 2 by the bearing pins 20 which are threaded into the side of the base. The coil spring 21 extends between lower jaw 16 and base 2 and is lodged in suitable seating grooves in jaw 16 and base 2 to confine the spring in service.

The upper jaw 18 of the separating clamp is pivoted towards the rear thereof to the bearing lugs 22 which extend upwardly from each side of lower jaw 16 substantially centrally thereof. The thin edge 23 corresponding to edge 12 of the holding clamp, and which also may be serrated, extends downwardly from the forward end of jaw 18 to clamp the lower end portions of sheets 14 of the set of forms 8 tightly against the lower jaw 16 when the clamp is closed, as will be described.

The rear end portion of jaw 16 projects diagonally upwardly from the body of the jaw and the generally rectangular frame member 24 is pivoted to each side of the jaw rear end portion.

The forward transverse bar of frame 24 engages the underside of upper jaw 18 and the lever arm 25 is secured to the center of the rear transverse bar of frame member 24 for actuation of the clamp by the operator. The light spring 26 is seated between jaws 16 and 18 of the clamp between bearing lugs 22 and normally biases the upper jaw 18 upwardly to maintain the jaws apart when the clamp is in open position.

In order to facilitate breaking of the perforations 26, one of bearing pins 20, as shown in Fig. 5 and in dotted lines in Figs. 1 and 3, is located lower and to the rear of the pin 20 on the opposite side of the base. In addition a longer leg 19 is employed with the lower offset pin 20. With this construction, under a tendency of the paper forms to stretch, by employing a greater radius between one of the pins 20 and the line at which the edge portions of the forms are clamped, there is a tendency of the perforations 26 to break first at one end and to continue to break thereafter across the forms rather than to all break at one time.

In operation of the machine the movable base 1 is first moved along rods 3 until it is spaced correctly from stationary base 2 to receive the set of forms 8 to be separated. The knurled set screws 5 are then threaded home against rods 3.

The holding clamp is next applied as in Fig. 3 by moving the lever arm 11 over and down towards forms 8 to clamp the head 7 of the set of forms between the depending edge 12 of upper jaw 9 and the top 6 of base 2, comprising the lower jaw of the clamp, as the operator applies pressure on lever arm 11.

As soon as the head 7 of the set of forms 8 is clamped as described, the operator presses downwardly on the lever arm 25 of the separating clamp pivoted to stationary base 2. This move-

ment of the lever arm closes the upper jaw 18 to clamp the lower ends of sheets 14 between the upper jaw 18 and lower jaw 16. Further movement of lever arm 25 pivots the entire separating clamp upon the bearing pins 20 away from the forward upright 17 and compressing coil spring 21, so that the sheets 14 are pulled away from head 7 breaking the perforations 26 such as those shown in Figs. 7 and 8 and leaving the shorter unperforated carbon sheets 15 attached to head 7. Fig. 3 shows the position of the separating clamp during the separation operation.

The set of forms are readily supported in the machine on the top of adjustable table top 6 and movable table top 16 before the separating operation is begun and are readily inserted in the clamp as the holding clamp is swung out of position and jaws 16 and 18 of the separating clamp are held open by light spring 26.

The machine is light in weight and portable, and is compact so that it can be used with a minimum space requirement on a desk or table.

In addition, the machine will accommodate sets of forms of various widths and is adjustable to handle forms of different lengths.

Various embodiments of the invention may be employed within the scope of the accompanying claims.

I claim:

1. A manually operable lightweight portable form separator machine for separating perforated form sheets from a pad head and from shorter sheets of said head interposed between the perforated sheets, which comprises a pair of spaced base members adapted to rest on a common support, means adjustably securing said base members in a selected spaced relation to accommodate selectively sheets of different length therebetween, a pivotal jaw member on one of said base members having a jaw extending laterally across the top of the base and adapted to move downwardly upon the top of the base member to clamp the free end of said perforated sheets therebetween, a manually operable hand lever secured to said jaw member to operate the same, a clamp pivoted to the other of said bases and extending across the same with upper and lower jaw members providing a mouth opening toward said first named jaw and base members to receive the head of said form sheet pad, means to bias said clamp to a normal loading position, stop means limiting the biased movement of said clamp, and a single manually operable hand lever secured to said clamp and disposed to close the clamp upon said head under pressure and thereafter to pivot the clamp bodily upon said base against said biasing means and in a direction away from said first named jaw and base members by a single stroke of said lever, said levers being disposed to be pressed downwardly toward the support for said base members when applying pressure to close the jaw and clamp whereby manual actuation of said levers by the two hands of an operator does not displace the machine from its support and an effective clamping pressure and tearing movement may be obtained.

2. A manually operable lightweight portable form separator machine for separating perforated form sheets from a pad head and from shorter sheets of said head interposed between the perforated sheets, which comprises a pair of spaced base members adapted to rest upon a common support, means to secure said base members in selective spaced relation to accommodate sheets of different length, means carried by one of said

base members to clamp the free end of said perforate sheets, a manually operable hand lever disposed to operate said clamping means by one hand of an operator, a clamp carried by the ether of said base members to clamp the head of said sheets, means pivotally supporting said last named clamp upon the corresponding base to pivot on a transverse axis disposed substantially below the position for the head of the sheets whereby pivotal movement of said clamp in a direction away from said first named clamp effects tearing of said sheets at a line of perforations adjacent the head and initial separation of the sheets, and a manually operable hand lever disposed to operate said second clamp and by a single operating stroke from the other hand of the operator to additionally pivot the clamp upon its base to effect separation of said sheets, said levers being disposed to be pressed downwardly toward the support for said base members in operation to prevent displacement of the machine from the support.

3. A manually operable lightweight portable form separator machine for separating perforated form sheets from a pad head and from shorter sheets of said head interposed between the perforated sheets, which comprises a pair of spaced base members adapted to rest upon a common support, means to secure said base members in selective spaced relation to accommodate sheets of different length, means carried by one of said base members to clamp the free end of said perforate sheets, a manually operable hand lever disposed to operate said clamping means by one hand of an operator, a clamp carried by the other of said base members to clamp the head of said sheets, means pivotally supporting said last named clamp upon the corresponding base to pivot on a transverse axis disposed substantially below the position for the head of the sheets whereby pivotal movement of said clamp in a direction away from said first named clamp effects tearing of said sheets at a line of perforations adjacent the head and initial separation of the sheets, means normally supporting said clamp upright upon said pivot and in loading position, and a manually operable hand lever disposed to operate said second clamp and by a single operating stroke from the other hand of the operator to additionally pivot the clamp upon its base to effect separation of said sheets, said levers being disposed to be pressed downwardly toward the support for said base members in operation to prevent displacement of the machine from the support.

4. A manually operable lightweight portable form separator machine for separating perforated form sheets from a pad head and from shorter sheets of said head interposed between the perforated sheets, which comprises a pair of spaced base members adapted to rest upon a common support, means to secure said base members in selective spaced relation to accommodate sheets of different length, means carried by one of said base members to clamp the free end of said perforate sheets, a manually operable hand lever disposed to operate said clamping means by one hand of an operator, a clamp carried by the other of said base members to clamp the head of said sheets, means pivotally supporting said last named clamp upon the corresponding base to pivot on a transverse axis disposed substantially below the position for the head of the sheets whereby pivotal movement of said clamp in a direction away from said first named clamp effects tearing

of said sheets at a line of perforations adjacent the head and initial separation of the sheets, and a manually operable hand lever disposed to operate said second clamp and by a single operating stroke from the other hand of the operator to additionally pivot the clamp upon its base to effect separation of said sheets, said levers being disposed to be pressed downwardly toward the support for said base members in operation to prevent displacement of the machine from the support, and said pivot supporting said last named clamp being disposed at an acute angle to the longitudinal center-line of the position of the sheets to effect a greater initial pivotal movement for said clamp at one side of the sheets than at the other side whereby tearing of said line of perforations is effected progressively at least initially.

5. A manually operable lightweight portable form separator machine for separating perforated form sheets from a pad head and from shorter sheets of said head interposed between the perforated sheets, which comprises a pair of spaced base members adapted to rest upon a common support, means to secure said base members in selective spaced relation to accommodate sheets of different length, means carried by one of said base members to clamp the free end of said perforate sheets, a manually operable hand lever disposed to operate said clamping means by one hand of an operator, a clamp carried by the other of said base members to clamp the head of said sheets, means pivotally supporting said last named clamp upon the corresponding base to pivot on a transverse axis disposed substantially below the position for the head of the sheets whereby pivotal movement of said clamp in a direction away from said first named clamp effects tearing of said sheets at a line of perforations adjacent the head and initial separation of the sheets, means normally supporting said clamp upright upon said pivot and in loading position, and a manually operable hand lever disposed to operate said second clamp and by a single operating stroke from the other hand of the operator to additionally pivot the clamp upon its base to effect separation of said sheets, said levers being disposed to be pressed downwardly toward the support for said base members in operation to prevent displacement of the machine from the support, and said pivot supporting said last named clamp being disposed at an acute angle to the longitudinal center-line of the position of the sheets to effect a greater initial pivotal movement for said clamp at one side of the sheets than at the other side whereby tearing of said line of perforations is effected progressively at least initially.
